UNITED STATES PATENT OFFICE.

CHAUNCEY E. FRAZIER, OF WASHINGTON, PENNSYLVANIA.

ANNEALING FURNACE.

Application filed January 6, 1922. Serial No. 527,287.

To all whom it may concern:

Be it known that I, CHAUNCEY E. FRAZIER, residing at Washington, in the county of Washington and State of Pennsylvania, a citizen of the United States, have invented or discovered certain new and useful Improvements in Annealing Furnaces, of which improvements the following is a specification.

10 My invention relates to heating furnaces, more specifically to kilns and annealing furnaces used for the heat treatment of articles formed of various materials, including glass, earthenware and metal, and it consists in 15 novelty of structure, whereby the distribution and localization of heat within the furnace chamber is more perfectly controlled. Generally speaking, my invention constitutes an improvement upon the structure 20 disclosed in Letters Patent of the United States, No. 1,389,583, granted me September 6, 1921. The particular object I have in view is such control of the temperature of the article under treatment as (in 25 the case of glassware) to reduce breakage to a minimum, and, whatever be the material, to achieve more perfect annealing.

While, as I have said, the invention is 30 applicable to annealing furnaces generally, and while I claim the invention in such wide applicability, I shall in the ensuing specification describe it, in exemplary way, in application to a leer for the annealing of glassware, this being the particular application 35 in which I have developed it.

In the accompanying drawings which 40 form part of this specification, Figure I is a view in vertical section longitudinally through a glass leer embodying my present invention, the plane of section being indicated by the broken line I—I, Figure IV; Figure II is a view in horizontal section on the plane indicated by the line II—II, Figure I. In Figure II the tiles which 45 constitute the roof of the annealing chamber are removed at the left-hand end, revealing the structure. Figure III is a view in horizontal section, on the plane indicated at III—III, Figure I. Figures IV and V are 50 views to larger scale and in transverse vertical section, the planes of section being indicated on Figure III by the correspondingly numbered lines IV—IV and V—V.

The leer shown in the drawings is of 55 muffle type and includes an annealing chamber 1 and a delivery passageway 3 continu-

ous with the annealing chamber, through which chamber and passageway an endless conveyor 4 may be made to advance, while a muffle chamber surrounds and envelops the 60 annealing chamber. These general features of construction are well known and require no extended description here. It is with the arrangement and the partitioning of the muffle chamber and the consequent course of 65 the stream of flaming gases or other products of combustion that my invention is concerned.

The muffle chamber has a floor 17, side 70 walls 19 and arched roof 20, the whole being built ordinarily of brickwork, framed, strengthened, braced, and tied together with iron in familiar manner, as illustrated in the drawings.

The annealing chamber is so built within 75 the muffle chamber that there are formed, (1) tunnel flues 21, 22, extending longitudinally beneath the annealing chamber, (2) side flues 23, 24, extending vertically between the side walls of the inner annealing 80 chamber and the outer muffle chamber, and (3) flues 25, 26, extending transversely beneath the floor of the annealing chamber and establishing communication between the vertical side-wall flues and the longitudinal 85 tunnel flues. As is best shown in Figure III, the furnace here shown is bilaterally symmetrical, and not only are the side walls with their flues duplicated on opposite sides of the structure, but the tunnel flues also 90 are duplicated on opposite sides of the mid-line, and there are two tunnels 21 and two tunnels 22, symmetrically arranged, while the connecting flues 25, 26 connect the vertical side-wall flues with the longitudinal flues 95 to constitute duplicate and symmetrical sets on opposite sides of the mid-line of the leer. The vaulted space above the roof of the annealing chamber and beneath the arched roof of the muffle chamber is divided by a 100 transverse partition 27, forming at the opposite ends of the leer and inlet chamber 28 commonly called the fire-box and an outlet chamber 29. These chambers are in immediate communication with the side-wall flues. 105

The inlet chamber or fire-box 28 is the primary combustion chamber. If producer gas is used as fuel a suitable burner or burners may be introduced in an opening or openings 30 in the roof of the chamber. If the 110 fuel be natural gas or oil the burner or burners may be placed in the opening or open-

ings 31 in the outer end wall of the chamber. The outlet chamber 29 opens to the stack or chimney 32, whereby draft is established through the whole. The outlet chamber is 5 divided centrally by a longitudinal partition 33, forming duplicate and symmetrically arranged chambers on opposite sides of the mid-line of the leir, and these duplicate chambers communicate separately with 10 the stack, each communication being controlled by an independently operable damper 34, as shown in Figure II. The general course of flow of the products of combustion is from the fire-box 28 through the opposite 15 side flues 23, 24 in front of the partition 27, thence through the transverse flues 25, 26, into the longitudinal tunnel flues 21, 22. From the tunnel flues the flow continues 20 through the other transverse flues and side flues at the rear of partition 27, into the twin 25 chambers constituting the outlet chamber 29, and thence to the stack. All of the vertical side flues, or such of them as may be desired, may be provided with dampers 35.

25 Coming now to the features wherein the present invention resides, and referring first to Figure III, it will be observed that the duplicate systems of flues are symmetrically arranged on opposite sides of the mid-line 30 of the leir; that each system includes two longitudinal tunnels 21, 22, beneath the floor of the annealing chamber; that those of the vertical side-wall flues nearer the partition wall 27, and on either side of partition wall 35 27, communicate, through transverse flues 26, with one (22) of the two tunnels, while the more remote of these vertical flues communicate, through transverse flues 25, with the other tunnel (21). Comparing Figures 40 II and III, it will be seen specifically that on the inlet side, the four vertical flues 24 nearest partition 27 open from chamber 28 to tunnel 22; and that on the delivery side the two vertical flues nearest partition 27 45 lead from tunnel 22 to the outlet chamber 29; while the more remote flues carry another stream from inlet to outlet chamber through tunnel 21. It will further be observed that those vertical flues which carry 50 the second stream (that, namely, which flows through tunnel 21) open into the outlet chamber 29 at a point nearer the stack, than do the flues which carry the stream which flows through tunnel 22. It is manifest that, 55 in consequence of this delivery at a point nearer to the stack, the draft through tunnel 21 will, other things being equal, be stronger than through tunnel 22, the stream of flame intenser, and the heating effect greater. 60 This is a condition which may be modified at will, according to the size, the number, and the grouping of the side-wall flues. And by means of the dampers 35 the condition is flexible and under control while operation progresses. Bringing into consid- 65

eration the symmetrical arrangement already explained of the two systems of passageways for the heat-giving flow, this first feature of my present invention will be 70 fully apprehended; temperature may at will be intensified locally, both longitudinally of and transversely of the annealing chamber; that is to say, according as the streams through the tunnels 21 preponderate over those through tunnels 22, temperature will 75 be built up at the intake end of the annealing chamber, and also along the mid-line of the annealing chamber. By movement of dampers 34 and 35 this condition may be modified at will. The two-sided arrangement, with the duplication of dampers, makes possible the development of higher temperature conditions on one side than on the other, either to compensate for some fortuitous local trouble or to meet some 80 other special need. The point is that the available supply of heat, in being imparted to the annealing chamber, may be distributed and localized to meet conditions, 85 whether constant and anticipated, or accidental and unanticipated. In this matter my furnace structure is flexible, beyond what has hitherto been employed in this art. 90

A further feature of invention resides in the particular shaping of the muffle chamber at the intake end of the leir—this is the left-hand end, as shown in Figs. I, II, and III of the drawings. I have alluded to the endless carrier 4 for conveying through the leir the material to be annealed. This carrier 95 universally takes the form of chains borne upon sprocket wheels. The sprocket wheels of course are arranged at the ends of the range of travel, and bearings must be provided for the axles of these sprocket wheels, 100 and housings for the bearings, and, at one end at least, driving connections must be made.

Confining attention to the intake end of the leir, the muffle chamber as hitherto constructed has not covered nor surrounded the sprocket wheels and that portion of the carrier which overlies and extends immediately adjacent to them. This has been due to the difficulty of carrying heat through such portion of the muffle as might cover the sprocket wheels; the wheels themselves constitute obstructions, in the way of extending the flue system in that direction. But when as in the operation of the leir as usually constructed (this when using mechanical carrying-in devices) the articles to be annealed are accumulated gradually at the intake end, and then the accumulation is loaded upon the end of the carrier projecting at the intake end beyond the reach of the muffle, they are as they accumulate subjected while still in unannealed condition to such inequalities of temperature in different parts as to be peculiarly subject to breakage. 130

I carry the muffle chamber and the annealing chamber forward (cf. Figs. I, II, and III), to overhang the sprocket wheels, and to afford an envelope of high temperature to the articles as they are brought to position on the carrier, I provide side-wall flues, 23^a, 23^a, for this overhang, but I carry these downward only so far as the matter of mounting the sprocket wheels allows (this ordinarily will be at or near the level of the horizontal reach of the carrier through the annealing chamber), and from that point I carry these flues horizontally, as indicated at 23^b, and cause them to open into the adjacent full-length flues 23 which open below to the tunnel flues 21 (cf., in this respect, Figs. IV and V). The stream of flame descending through the side-wall flues of the overhang at the intake end of the leer, will go to one pair of longitudinal tunnel flues, and the stream descending through more remote side-wall flues, will go to another tunnel flue, and the draft conditions in the two streams may be varied relatively by varying the setting of the dampers in the side-wall flues.

The side-wall panels 13 of the main portion of the annealing chamber are preferably formed of tile, but in this extension which I am now describing, these panels will preferably be made of cast iron, because of the greater heat conductivity of that material.

I have designated with the numeral 40 peep-holes arranged in the opposite side walls of the furnace which may be located at any desired point or points.

It will be understood that my invention is susceptible of considerable modification, and I do not desire to limit it within the scope defined by the terms of the appended claims.

I claim as my invention:

1. In an annealing furnace the combination with a leer chamber of a fire-box overlying said leer chamber, a plurality of tunnel flues extending longitudinally beneath said leer chamber, a series of side-wall flues and transverse bottom flues connecting said fire-box with said tunnel flues, the side-wall flues toward the intake end of said leer connecting with one of said tunnel flues and the side-wall flues more remote from the intake end connecting with another of said tunnel flues, a chimney with which said tunnel flues communicate, and means for varying the draft conditions in the streams of flame and gas which flow from the fire-box to the chimney through the said severally connected sets of side-wall flues.

2. In an annealing furnace, the combination with a leer chamber, of an inlet chamber and a succeeding outlet chamber above the leer chamber, a plurality of longitudinal tunnel flues beneath the leer chamber, a fire-box overlying the leer chamber, a plurality of tunnel flues extending longitudinally beneath said leer chamber, a series of

and a series of side-wall flues and transverse bottom flues connecting said inlet and outlet chambers with said tunnel flues, the side-wall flues near the opposite ends of the furnace being connected to one of said tunnel flues and the intermediate side-wall flues being connected to another of said tunnel flues.

3. In an annealing furnace, the combination with a leer chamber, of an inlet chamber and a succeeding outlet chamber above the leer chamber, two pairs of longitudinal tunnel flues beneath the leer chamber and disposed symmetrically on each side of its medial line, a series of vertical side-wall flues on each side of the leer chamber opening into said inlet and outlet chambers, and transverse flues connecting the bottom ends of said side-wall flues with said tunnel flues, the opposite side-wall flues near the opposite ends of the furnace being connected with the tunnel flues of one pair and the intermediate side-wall flues with the tunnel flues of the other pair.

4. In an annealing furnace, the combination with a leer chamber, of an inlet chamber and a succeeding outlet chamber above the leer chamber, means for introducing heating fluid into the inlet chamber, a stack connected to the outlet chamber, longitudinal tunnel flues beneath the leer chamber and on opposite sides of its medial line, vertical side-wall flues and transverse bottom flues connecting the inlet chamber and the outlet chamber on one side of the furnace with one of the tunnel flues and on the opposite side of the furnace with another tunnel flue, and means for controlling the flow of the heating fluid on each side of the system independently of the other.

5. In an annealing furnace having inner and outer walls, partitions dividing the space between the walls transversely into inlet and outlet rooms above, longitudinally into tunnel flues below, and vertically into opposite side-wall flues communicating with the rooms above, side-wall flues on one side of the furnace also communicating with one of the tunnel flues, and side-wall flues on the opposite side of the furnace communicating with another tunnel flue, means for maintaining a flow of a heating medium through the rooms and flues, and means for controlling such flow on one side independently of the other.

6. In a muffle leer a leer chamber, means for conveying ware through the leer chamber such means including an endless conveyor borne at the intake end of the leer chamber upon a sprocket wheel, the side walls and roof of the leer chamber extending forwardly above and on either side of the sprocket wheel of the said conveyor, a fire-box overlying the leer chamber, a plurality of tunnel flues extending longitudinally beneath said leer chamber, a series of

side-wall flues leading from said fire-box to said tunnel flues, the side-wall flues adjacent the sprocket wheel at the intake end of the leer leading to one of said tunnel flues 5 and the side-wall flues more remote from the intake end connecting with another of said tunnel flues, a chimney with which said tunnel flues communicate, and means for varying the draft conditions in the streams 10 of flame and gas which flow from the fire-box to the chimney through the said severally connected sets of side-wall flues.

7. In a muffle leer a leer chamber, a fire-box overlying said leer chamber, a plurality 15 of tunnel flues extending longitudinally beneath said leer chamber, side-wall flues leading through the opposite side walls of the

structure and connecting said fire-box with said tunnel flues, the side-wall flues toward the intake end of the leer and the side-wall 20 flues more remote from the intake end leading to different tunnel flues, a chimney with which said tunnel flues communicate, and means for varying draft conditions in the streams of flame and gas both as between 25 those near to and those remote from the intake end of the leer and also as between those on the two sides of the leer.

In testimony whereof I have hereunto set my hand.

CHAUNCEY E. FRAZIER.
